CLAIM

The ornamental design for a dough divider-rounder, as shown and described.

DESCRIPTION

FIG. 1 is a front elevational view of a dough divider-rounder showing my new design;

FIG. 2 is a left side elevational view of the dough divider-rounder of FIG. 1;

FIG. 3 is a right side elevational view thereof;

FIG. 4 is a rear elevational view thereof; and,

FIG. 5 is a top plan view thereof.

No claim being made to the bottom view of the dough divider-rounder.
